Julius Josephs

By his Attorney

Wm Wallace White

UNITED STATES PATENT OFFICE.

JULIUS JOSEPHS, OF NEW YORK, N. Y., ASSIGNOR TO THE CROFUT & KNAPP COMPANY,
OF NEW YORK, N. Y.

CAP.

1,352,968.

Specification of Letters Patent. Patented Sept. 14, 1920.

Application filed May 20, 1920. Serial No. 382,698.

To all whom it may concern:

Be it known that I, JULIUS JOSEPHS, a citizen of Russian Poland, residing in the city, county, and State of New York, have 5 invented new and useful Improvements in Caps, of which the following is a specification.

My invention relates to caps and has as its principal object the provision of a cap 10 suitable for use in winter weather, which is provided with means for covering the ears when desired and yet may at other times be worn without giving the appearance of such means. Further objects are to provide a cap 15 with detachable ear flaps, which may be detachably secured to the cap, for instance by means of snap fasteners, when it is desired that the flaps be put in use; and to provide means located within the cap for carrying 20 such ear flaps when not in use, or when detached. A further object of the invention is to provide means for carrying the ear flaps entirely from the lining of the cap, so 25 that its exterior appearance is unchanged; and, if desired, the ear flaps may be left at home when the cap is worn in warm weather. Further provision may be made whereby the ear flaps extend down under 30 the chin and are held firmly in place by snap fasteners thereunder.

With the foregoing objects in mind, my invention consists in the construction, combination and arrangement of parts herein described, illustrated and claimed.

In the accompanying drawings, in which similar reference characters designate corresponding parts in all views, I have illustrated a preferred embodiment of my invention. Referring to these drawings,

40 Figure 1 is an elevation of a cap embodying the invention, showing the ear flaps in position for use;

Fig. 2 is a view looking upward at a cap, with parts broken away, and showing the 45 ear flaps in carrying position;

Figs. 3 and 4 show details of an ear flap and its attachment to the cap;

Fig. 5 is a sectional elevation taken approximately on the longitudinal center line 50 (5—5 of Fig. 2) of the cap showing the ear flaps in carrying position; and

Fig. 6 is a transverse section taken approximately on the line 6—6 of Fig. 2.

Referring to these drawings, 1 designates 55 a cap preferably provided with a band, 2,

and a lining, 3. In the band 2, approximately over the ears of the wearer, are located means to which ear flaps, 6, may be detachably secured, preferably consisting of the socket portions of snap fasteners, 4. 60 Adapted to engage said means are suitable means provided on the ear flaps, preferably consisting of the projecting portions, 5, of the snap fasteners, which portions 5 are secured to the upper parts of the ear flaps 6. 65

These ear flaps 6 are preferably made long enough to extend down under the chin, being narrower at their lower portions, and are provided at their lower portions with means, such as snap-fasteners, 7, with which 70 they may be fastened under the chin. Preferably, several snap-fasteners, 7, are secured to the lower part of each flap 6, so that the proper one may be selected for use to suit the particular person wearing the cap. 75

When the ear flaps 6 are not desired to be used as such, the snap-fasteners 7 are opened, and the flaps disengaged from the cap by opening the snap-fasteners 4, 5, by means of which they are held to the cap. These 80 flaps are then placed in the interior of the cap between the top of the cap and a strip, 8, of material which extends preferably longitudinally of the cap and is secured to the top of the cap, or preferably to the top of 85 the lining, 3, by means of stitching, 9, located near the end of the strip, 8, leaving the central portion, 10, of the strip free from the top, and thus forming a pocket into which the ear flap may be inserted. 90 The strip 8 is made of sufficient width to adequately support the ear flaps, and the upper portion of the cap is preferably constructed of greater width than the band, so that the end portions of the flap when in 95 carrying position tend to be supported by the sides of the cap.

Having now described my invention, I claim and desire to secure by Letters Patent:

1. A cap comprising an outer covering, a 100 lining secured thereto at the band, ear flaps, snap fasteners, the projecting portions thereof secured to said ear flaps, and the socket portions to the interior of the cap band, and a strip extending longitudinally of the cap 105 stitched at its ends to the interior of the lining of the top of the cap, and free at its central portion to provide means for carrying the flaps when detached.

2. In a cap, the combination comprising 110

ear flaps, snap fasteners adapted to detachably connect said flaps with the interior of the cap, snap fasteners adapted to detachably connect said flaps beneath the chin of a wearer, and a fore and aft strip secured to the top of the cap within the cap at its ends, the central portion forming means to hold the flaps when detached.

3. In a cap, the combination comprising
10 ear flaps, snap fasteners secured thereto and to the interior of the cap band, and a strip stitched to the top of the cap at its end portions and free in the central portion forming means for carrying the flaps when
15 detached.

4. In a cap, the combination comprising detachable ear flaps and a longitudinal strip stitched to the top of the cap at its end portions, and free in the central portion forming means for carrying the flaps when 20 detached.

5. In a cap, the combination comprising detachable ear flaps and a strip secured at its ends to the top of said cap on the interior for carrying said ear flaps when not in 25 use.

In testimony whereof I have signed my name to this specification.

JULIUS JOSEPHS.
